ELECTROHYDRAULIC POSITION CONTROL
SYSTEMGeorge Agins, Brooklyn, N. Y., assignor to Arma
Corporation, a corporation of New York

Application May 12, 1936, Serial No. 79,290

25 Claims. (Cl. 318—30)

1

This invention relates to electro-hydraulic position control systems and has particular reference to electro-hydraulic systems for positioning gun mounts in accordance with movements of a remote observation instrument, although the invention is not limited to that use.

In positioning a gun in train in accordance with the movement of the director, it is not only necessary to provide ample power to drive the heavy gun mount, but it is also necessary to control the drive with the degree of accuracy required to secure accurate gun direction, and this requires compensation for errors resulting from the transmission of movements from the director to the gun mount, some of which are due to the mass, inertia and momentum of the heavy gun mount. Similar errors occur in positioning the gun in elevation and/or depression and must be compensated for.

In accordance with the present invention, a position control system, especially adapted for positioning gun mounts, is provided, in which the gun mount is driven by a variable speed hydraulic gear controlled electrically by means responsive not only to movements of the observation instrument and calculating mechanism of the remote director, but also to error-introducing movements of the director, the gun mount and the hydraulic gear. The errors, which are compensated for electrically, include hunting or oscillation of the gun mount and hydraulic gear at the end of a movement thereof, velocity and acceleration lags due to compensating means, and the like.

An electrical synchronizing differential mechanism is also provided for automatically effecting approximate agreement between the director and the gun mount in case of large deviation between them, so as to enable high-speed registering mechanism to assume control and position the gun mount in exact agreement with the director. Arrangements are provided for selectively switching the control mechanism from automatic to manual regulation, and also to direct manual mechanical operation of the hydraulic gear, as well as other items of regulation insuring accuracy and rapidity of response.

It will be seen that the electro-hydraulic control means of this invention is extremely sensitive and accurate in its operation, despite the large masses which are moved thereby, so that the gun mount may be positioned as rapidly and with as great accuracy as can a much lighter device with the control systems employed heretofore.

For a more complete understanding of the

2

invention, reference may be had to the accompanying drawing in which Fig. 1 illustrates diagrammatically and schematically the electrical and mechanical arrangement of the electrohydraulic position control system of this invention, and Fig. 2 illustrates diagrammatically one form of converter for converting the alternating current signal into corresponding direct current.

Referring to Fig. 1, numeral 10 designates an observation instrument such as a director which is adjustable in elevation and train while following a moving target or a target which is stationary while the vessel or other support on which the director is mounted moves. 11 represents the gun mount, which is usually located at a point remote from the director 10 and is adapted to be driven automatically by the director 10 to be aimed on the selected target, suitable corrections for parallax and the like being introduced automatically through differential 15 by instrument 15', having range and target bearing inputs, to compensate for the variation in the angle of fire due to displacement of the director 10 and the gun mount 11. In the following description, the control of the gun mount in train will be described, it being understood that the same or similar mechanism may be used for directing the gun in elevation and/or depression.

Automatic control

Assuming that automatic control is desired, transfer switch 12 is adjusted in such a way that opposite contacts of the two left-hand rows *a* of contacts are bridged by brushes 13 in the manner indicated by the dotted lines.

The director 10 is provided with a ring gear 14 rotating in a substantially horizontal plane as the director 10 is moved in train. Meshing with gear 14 are pinion 16 and gear 17, the former being operatively connected to a high speed transmitter 18 and the latter to a low speed transmitter 19. These transmitters are preferably of the three-phase self-synchronous type, although other equivalent transmission devices may be used with equal facility, and their relative angular displacement ratio is preferably thirty-six to one. The terminals of the stator of the high speed transmitter 18 are connected by wires 20 through transfer switch 12, contacts 21, 22 and 23, to the terminals of the rotor of high speed regulator 24, which is connected by shaft 25 and the bevel gears 26 to the drive shaft 27 of the variable speed hydraulic gear 28 actuated by constant speed motor 29 and connected through shaft 27 by bevel gears 28' to the turn table of the gun mount 11.

The hydraulic gear 28 may be of more or less conventional design, comprising a tilt box in end A whose angle of tilt by control shaft 38 determines the rate of speed variation at which the drive shaft 27 is driven by the B end as compared to the constant speed input of actuating motor 29. Tilting of the tilt box from one side of neutral vertical position to the other reverses the direction of rotation of the drive shaft 27.

The position of the rotor of the high speed regulator 24 determines the voltage across the secondary terminals 29' and 30 of the stator of the high speed regulator 24. The terminals 29' and 30 are connected by wires 31 to the converter 32, forming no part of the present invention, but arranged to convert an alternating voltage of varying amplitude and reversible phase into a direct current voltage of proportional magnitude and reversible polarity. The converter 32 may be of any desired form, and by way of example, may be constructed and arranged as illustrated and described in copending application Serial No. 78,944, filed May 9, 1936, by applicant.

For convenience, the construction of the converter 32 is illustrated herein by Fig. 2, and may include the input transformer 140 connected to the wires 31 and having two secondary windings 141 and 142, a bias transformer 143 supplied from the alternating current source 103 and having two secondary windings 144 and 145, and two rectifier bridges 146 and 147 with rotating resistors 148 and connected in series with secondary windings 141, 144 and 142, 145, respectively. These rectifier bridges 146 and 147 are so connected that the fixed alternating current voltage in the secondary circuits of 144 and 145 is added to the signal voltage in one bridge and subtracted from that in the other bridge, depending upon the direction of deviation between the director 10 and the gun mount 11. The resulting proportional direct current voltages are opposed and the voltage output of the converter 32 has a magnitude and direction determined by the difference between the voltage output of the bridges 146 and 147 and will reverse as the phase of the input signal reverses. When the deviation is zero, the voltage output of the rectifier bridges is equal and thus they nullify, so that the voltage output of the converter is zero. To the output of the converter 32 are added the voltages generated in the director generator 33 connected by pinion 34 to the spur gear 14 of director 10, and the gun mount and control shaft damping generators 35 and 36. Damping generator 35 is driven by drive shaft 27 through the beveled gears 37, while damping generator 36 is driven from the control shaft 38 of variable speed hydraulic gear 28 by shafts 82 and 83 and bevel gears 84 and 85.

The director generator 33 is connected in the output terminals of converter 32 by wires 40 and 41, and the damping generator 35 is connected by wire 42 in series with the control shaft generator 36, which is connected to an input terminal of inverter 44 by wire 43. The resultant total direct current voltage is applied as input to the inverter 44, which functions to change the direct current input voltage of varying magnitude and reversible polarity to an alternating current voltage of proportional amplitude and reversible phase. The construction of the inverter forms no part of the present invention and may be of the form illustrated in copending application Serial No. 73,852, filed April 11, 1936.

The output voltage of inverter 44 is stepped up by input transformer 45 and applied to the 75

grids of the two pairs of vacuum tube control rectifiers 46 and 46', appropriate filament transformer 47, grid bias transformer 48, and power transformer 49 arrangements being provided.

Connected in the plate circuits of the two rectifiers 46, 46' is the hydraulic gear control motor 50. The essential portion of the control circuit of rectifiers 46' is traceable by wires 50', front contact 51' of closed limit relay 52, wire 53, bridged contacts 54 of transfer switch 12, wire 55 and control motor 50. For the rectifiers 46 the circuit is traceable by wire 62, front contact 61 and center contact 59 of limit relay 60, wire 58, center contact 57 of limit relay 52, and wire 56 to control motor 50. This motor 50 acts through magnetic clutch 51 to properly position the control shaft 38 of the variable speed hydraulic gear 28. Magnetic clutch 51 is normally closed, the circuit of which may be traced from negative terminal of direct current supply 63, bridged transfer switch 12, contacts 64, wire 65, contact 66, wire 67, clutch 51 winding, wire 68, and the normally closed contacts of relays 69 and 70 to the other side of the line.

With the magnetic clutch 51, the high speed transmitter 18 system, the director generator and their appurtenant parts energized by the adjustment of transfer switch to position *a* for automatic operation, exact control is maintained by the high speed transmitter 18 when the angular position of gun 11 in train is initially in approximate agreement with the horizontal deflection of the director 10. This exact control takes place when the windings of the rotor of the high speed regulator 24 are moved by gun mount 11 into registry with the windings of the stator, so that the voltage across its output terminals 29' and 30 is zero and there is no energization of the hydraulic gear control motor 50. However, there is a tendency of the gun mount 11 to oscillate or hunt and in order to compensate for this hunting, the damping generator 35 is provided, and is geared to the drive shaft 27 of the hydraulic gear 28, so that the voltage developed across the terminals 42, 71 of the damping generator 35 is proportional to the velocity of the gun mount 11 and may be applied, at proper polarity, to suppress any tendency of the gun mount 11 to sustain an oscillation. Similarly, since the control shaft generator 36 is geared to the shaft 38 of control motor 50, the voltage developed across its terminals 42, 43 is proportional to the speed of the control motor 50 and may be utilized, at proper polarity, to suppress any tendency to hunt due to a lag in the response of control motor 50.

The damping generator 35 and the control shaft generator 36 are connected in series and the voltages developed by both generators are combined. The deviation voltage of regulator 24 which is applied to the converter 32 will be zero when the gun mount 11 is in exact positional agreement with the director 10, and the sum of the voltages applied to the inverter 44 must be zero for constant velocity conditions of the system. The damping generator 35 produces a voltage for damping purposes but at the same time it introduces an error to the system in the form of a velocity lag, so that the deviation voltage across the regulator 24 terminal 29' and 30 will not be zero. In order to compensate for this velocity lag, the director generator 33 geared to the director 10 is employed, and develops a voltage across its terminals 72, 73 which is proportional to the velocity of the director 10. Inasmuch as the velocities of movement of

the director 10 and gun mount 11 are approximately the same, a portion of this voltage, predetermined by the relative values of resistances 74 and 75, is proportional to the damping generator 35 voltage and consequently is introduced into the circuit of damping generator 35 by connections traceable from resistances 74 and 75 by wire 76, segment 77, adjustable brush 78' of synchronizing differential 78, whose function is to be described, wire 79, connected contacts 80 10 and 81 of transfer switch 12 and wire 71. The magnitude of this compensating voltage is such as to compensate for the velocity lag introduced by damping generator 35, whereby the deviation between the director 10 and gun mount 11 for constant velocity conditions is reduced to a negligible quantity. It will be observed that this compensation for velocity lag introduces no disturbing factor, for it is independent of the speed of power motor 29 of the hydraulic gear 28, and of any variations in the field excitation of director and damping generators 33 and 35, respectively, since any fluctuations in the field voltages of these generators occur simultaneously, due to their common source 63, and have the same effect on both, so that the sum of their output voltages remains zero.

Another compensation is provided. In conventional types of variable speed hydraulic gears, such as 28, the speed of the B end drive shaft 27 is proportional to the displacement of the A end control shaft 38 from neutral position and the direction of rotation of the drive shaft 27 depends upon the direction of displacement of the control shaft 38 from this neutral position, so that acceleration of the drive shaft 27 is proportional to the velocity of the control shaft 38. Inasmuch as the voltage developed by the control shaft generator 36 is proportional to the speed of the control shaft 38, to which it is directly connected by shaft 82 and 83 and bevel gears 84 and 85, and is also proportional to the acceleration of drive shaft 27, it follows that for any acceleration of drive shaft 27 the voltage across the output terminals 29', 30 of the high speed regulator 24 cannot be zero, but must be of sufficient magnitude to cause a voltage, equal and opposite to that of the control shaft generator 36, to be developed across the output terminals 41, 86, of converter 32. This results in an acceleration lag which, although considerably less than the velocity lag, nevertheless requires compensation for accurate control.

This compensation is introduced by means of an inductance 87 in series with the resistance 74, so that, although the voltage across the terminals of this inductance is zero for constant velocity of the director 10, because the current is constant, nevertheless, for an acceleration of the director 10 an additional voltage proportional to the rate of change of the current is developed in inductance 87. Since the resistances 74 and 75 are large compared to the inductance 87, the current flowing through the inductance is sensibly proportional to the voltage developed across the terminals 72, 73 of the director generator 33 or proportional to the velocity of director 10, so that the voltage across the terminals of inductance 87 is proportional to the acceleration of director 10. Consequently, compensation for the acceleration lag introduced by control shaft generator 36 is provided. Also, in this way the acceleration lag due to other causes such as regulation of hydraulic gear motor 29, elasticity of the

hydraulic gear 28, and the like, is compensated for.

In case of a large initial deviation between the director 10 and the gun mount 11, the low-speed transmission system is employed, which is arranged to drive the gun mount to approximate agreement with the position of the director 10, so that the high speed transmission system just described may automatically assume control. As aforementioned, the high-low speed gear ratio is preferably thirty-six to one. The initial impulse to obtain this approximate agreement of the director and gun mount is provided by the synchronizing differential 78, the rotor 88 of which is connected by wires 89 to the low speed transmitter 19 driven by the director 10 through gears 14 and 17 and shaft 90. The stator 91 of synchronizing differential 78 is connected by wires 92 to low speed regulator 93, geared to the gun mount 11 by gears 94 and 95, shaft 25, bevel gears 26, shaft 27, and bevel gears 28', so that deviation of the rotor 88 of synchronizing differential 78 from a predetermined position will be proportional to the deviation between the gun mount 11 and the director 10.

During approximate angular agreement of the gun mount 11 with the director 10, the brush 78' carried by the shaft 96 of differential rotor 88 engages segment 77 and the high speed regulator 24 assumes and maintains control in the manner described. During any greater deviation of the gun mount 11, brush 78' engages either segment 97 or 98, depending upon the direction of the deviation, thus depriving high speed regulator 24 of control by opening the output circuit of converter 32 and connecting the appropriate half of potential divider 99 in the inverter circuit. The center tap of the potential divider 99, which is supplied with direct current at constant voltage, is connected by wire 100 to wire 86 of the inverter 44 input. Accordingly, the polarity of the inverter 44 input depends upon the direction of the deviation between the director 10 and the gun mount 11. Thus, when brush 78' engages segment 98, the polarity of input 43 is positive and when it engages segment 97 it is negative. The voltage across both halves of the potential divider 99 are predetermined, so that the control motor 50 is energized by grid control rectifiers 46 or 46', depending upon the phase of the inverter 44 output voltage, to rotate in the proper direction to adjust variable speed gear 28 to drive the gun mount 11 and damping generator 35 at such speed that the voltage developed by the damping generator 35 is equal and opposite in polarity to the voltage across that half of the potential divider 99 which is connected in the circuit by brush 78'.

The gun mount 11 is accordingly driven in a direction such as to reduce the angle of its deviation from the director 10, and, in so moving, it rotates the rotor of low speed regulator 93, the field winding 101 of which is energized from alternating current source 103 through bridged contacts 102 of transfer switch 12, so that stator 91 of synchronizing differential is energized to cause rotor 88 to rotate through a proportional angle and move brush 78' into reengagement with segment 77, thus transferring the control to high speed regulator 24 for operation in the manner described.

Local control

If local power control is desired instead of automatic control, transfer switch 12 is adjusted so that opposite contacts of the two right-hand rows

of contacts *c* are bridged by brushes *13*, and breaks the connection between opposite contacts of the two left-hand rows of contacts *a* so that high and low speed director transmitters *18* and *19*, director generator *33*, synchronizing differential *78*, contacts *77*, *97*, *98*, inductance *87* and resistance *75* are simultaneously disconnected. Bridging of the lower contacts *105* and *106* connects one side of the alternating current supply *103* to the field winding *107* of local power transmitter *108*, the other side of which is connected directly to supply *103*. Similarly, the field winding *109* of local power control generator *110*, geared by gears *122* and *123* to shaft *121* of local transmitter *113*, is connected to direct current supply *63* through bridged contacts *66* and *111* and wires *112*. The rotor *113* of local transmitter *108* is connected through bridged contacts *114*, *115* and *116* and wires *20* to the rotor of high speed regulator *24*. One brush of local control generator *110* is connected by wires *117* and *41* in the output of converter *32*, and the other brush through switch contact *104* and *81* and wire *71* is connected to damping generator *35* in series with control shaft generator *36*, in turn connected by wire *43* to the inverter *44* input.

The control motor *50* is reconnected in the circuit by bridging of switch contacts *118*. Control is accordingly transferred to handwheels *119* connected by bevel gears *120* and shaft *121* to the rotor *113* of local transmitter *108*, the displacement of which causes a phase displacement in high speed regulator *24*, resulting in energization of control motor *50* for adjustment of the control shaft *38* of variable speed gear *28*, so that gun mount *11* is driven through a proportionate angle determined by the consequent angular agreement of the high speed regulator *24* with the local transmitter *108*, so that current no longer flows in the amplifier circuit. With this follow-up arrangement, the reaction of the variable speed hydraulic gear *28* control shaft *38* on the handwheels *119* is eliminated, and there is no velocity lag, both items resulting in greater ease of control.

Direct manual control

For direct manual control, transfer switch *12* is adjusted to the third position. Inasmuch as the opposite contacts of the two center rows *b* are all jump-connected, the actuation of the switch to this position has no effect except to disconnect the majority of the elements employed for automatic and local control. Connected to the handle of the switch *12* by means of links *125*, or the like, is a friction clutch *126*, one side of which is connected to shaft *25* and the other side thereof is connected by pinion *127* to gear *122* in shaft *121* controlled by handwheels *119* and connected to local transmitter *108*. The clutch *126* is disengaged during automatic or local control, but when the handle of switch *12* is shifted to the position for direct manual control, links *125* are actuated to engage clutch *126*. Inasmuch as disconnection of transfer switch contacts *66* and *111* or *64*, by shifting the switch *12* to the direct manual control position *b* disengages magnetic clutch *51*, the handwheels *119* are directly connected to the control shaft *38* of variable speed gear *28* by bevel gears *120*, shaft *121*, gears *122* and *121*, clutch *126*, shaft *25*, differential *128*, shaft *129*, and bevel gears *130*. Rotation of the handwheels *119* in one direction accordingly adjusts the variable speed gear *28* to drive gun mount *11* in the appropriate direction, the back drive through shaft *27* bevel gears *26*, differential *128* and shaft *75*

129 gradually restoring control shaft *38* to its initial position when the gun mount has been moved through the angle designated by the operator in rotating handwheels *119*.

In order to prevent interference between the gun mount *11* and other adjacent objects which may limit train of the mount in either direction, limit stop mechanism *131* is provided. This mechanism includes a screw *132* rotated by bevel gears *133* driven by shaft *25*, so that screw *132* turns through an angle proportional to the angle of train of the gun mount *11* and to the deflection of the control shaft *38*. Inasmuch as the motion of control shaft *38* is small compared to the train of the gun mount *11*, the position of the nut *134* is approximately equivalent to the gun position. When the gun mount *11* nears the limit of its permissible movement in one direction, nut *134* engages and opens either limit contact *135* or *136*, deenergizing the holding circuits of corresponding limit relays *60* or *52*, respectively, which, by means of respective open contacts *61* or *51'*, break the plate circuits of grid control rectifiers *46*, thus stopping control motor *50* and, consequently, movement of the gun mount *11* in that direction before it is driven against the gun stops.

Opening of center contacts *57* or *59* of relays *52* or *60*, respectively, deenergizes the corresponding winding of clutch relay *70*, which in turn releases its armature *137* to deenergize magnetic clutch *51*, mechanically disconnecting control motor *50* from hydraulic gear *28* control shaft *38*. The other of the two limit relays *52* or *60* remains energized and the corresponding winding of relay *70* is placed in series with the armature of control motor *50*, so that when the rectifiers *46'* are energized, tending to drive the control motor *50* in the opposite direction, the armature current through the said winding of relay *70* will close its armature *137* to reenergize magnetic clutch *51* and reconnect the control motor *50* to the control shaft *38*, so as to permit the gun mount *11* to be driven back from its stop.

Immediately after opening either contact *135* or *136*, nut *134* engaged and was stopped by abutment *138* or *139*, respectively, and screw *131* was locked against further rotation, so that control shaft *38* is moved through differential *128* by the drive shaft *27* in a direction such as to bring the gun mount *11* to rest. This operation of the limit stop mechanism is the same for both automatic and local power control, and for the direct manual control, its operation is mechanical.

I claim:

1. In a system for positioning a controlled member in accordance with the movement of a controlling member, the combination of motive means for actuating the controlled member, electrical means responsive to positional disagreement between the members for controlling said motive means, and electrical means jointly responsive to the algebraic sum of the positional disagreements of both members and the rate of change thereof for regulating said first electrical means.

2. In a system for positioning a controlled member in accordance with the movement of a controlling member, the combination of motive means for actuating the controlled member, electrical means responsive to positional disagreement between the members for controlling said motive means, and electrical means jointly responsive to the positional disagreement and a change in the rate of speed of movement of both of said members for regulating said first electrical means.

3. In a system for positioning a controlled member in accordance with the movement of a controlling member, the combination of motive means for actuating the controlled member, electrical means responsive to positional disagreement between the members for controlling said motive means, electrical means responsive to the velocity of movement of either of said members for regulating said first electrical means, and electrical means jointly responsive to the positional disagreement and a change in the rate of movement of both of said members for modifying the regulation of said first electrical means by said second electrical means.

4. In a system for positioning a controlled member in accordance with the movement of a controlling member, the combination of motive means for actuating the controlled member, electrical means responsive to positional disagreement between the members for controlling said motive means, electrical means responsive to the velocity of movement of said controlling member for regulating said first electrical means, and electrical means jointly responsive to the positional disagreement and a change in the rate of movement of both of said members for modifying the regulation of said first electrical means by said second electrical means.

5. In a system for positioning a controlled member in accordance with the movement of a controlling member, the combination of driving power means for the controlled member, electrical means responsive to positional disagreement between the members, a control motor for said power means energized by said electrical means for causing said power means to drive the controlled member in accordance with the movement of the controlling member, and a generator actuated by said control motor for modifying the output of said electrical means to effect a damping of the movement of said controlled member.

6. In a system for positioning a controlled member in accordance with the movement of a controlling member, the combination of driving power means for the controlled member, electrical means responsive to positional disagreement between the members, a control motor for said power means energized by said electrical means for causing said power means to drive the controlled member in accordance with the movement of the controlling member, and electrical means responsive to movement of both of said members for modifying the output of said electrical means to effect a damping of the movement of said controlled member.

7. In a system for positioning a controlled member in accordance with the movement of a controlling member, the combination of driving power means for the controlled member, electrical means responsive to positional disagreement between the members, a control motor for said power means energized by said electrical means for causing said power means to drive the controlled member in accordance with the movement of the controlling member, and electrical means responsive to the algebraic sum of the movements of both of said members for modifying the output of said electrical means to effect a damping of the movement of said controlled member.

8. In a system for positioning a controlled member in accordance with the movement of a controlling member, the combination of driving power means for the controlled member, electrical means responsive to positional disagreement between the members, a control motor for said power means

energized by said electrical means for causing said power means to drive the controlled member in accordance with the movement of the controlling member, a generator actuated by said controlling member, a generator actuated by said controlled member, and means for modifying the output of said electrical means with the joint outputs of said generators to effect a damping of the movement of said controlled member.

10 9. In a system for positioning a controlled member in accordance with the movement of a controlling member, the combination of driving power means for the controlled member, electrical means responsive to positional disagreement between the members, a control motor for said power means energized by said electrical means for causing said power means to drive the controlled member in accordance with the movement of the controlling member, a generator actuated by said controlled member, and means for modifying the output of said electrical means with the joint output of said generators to effect a damping of the movement of said controlled member.

15 10. In a system for positioning a controlled member in accordance with a controlling member, the combination of driving power means for the controlled member, a control motor therefor, means responsive to a predetermined positional disagreement between said members for inducing a signal voltage corresponding in magnitude and direction to the magnitude and direction of such positional disagreement, a plurality of thermionic relays having plate circuits selectively controlling 30 said control motor, one of said relays being responsive to voltage in one direction and the other relay being responsive to voltage in the opposite direction, and means for impressing said signal voltage jointly on said relays for energizing the 35 control motor to cause said power means to drive the controlled member into positional agreement with the controlling member.

11. In a system for positioning a controlled member in accordance with a controlling member, the combination of driving power means for the controlled member, a control motor therefor, means responsive to a predetermined positional disagreement between said members for inducing a signal voltage corresponding in magnitude and direction to the magnitude and direction of such positional disagreement, a plurality of thermionic relays having plate circuits selectively controlling said control motor, one of said relays being responsive to voltage in one direction and the other relay being responsive to voltage in the opposite direction, means for impressing said signal voltage jointly on said relays for energizing the control motor to cause said power means to drive the controlled member into positional agreement with the controlling member, and means responsive to a positional disagreement between said members in excess of the said predetermined positional disagreement for impressing additional voltage on said relays to energize said control motor to cause said power means to move the controlled member to said predetermined positional disagreement for assumption of control by said first responsive means.

12. In a system for positioning a controlled member in accordance with a controlling member, the combination of driving power means for the controlled member, a control motor therefor, means responsive to a predetermined positional disagreement between said members for inducing a signal voltage corresponding in magnitude

and direction to the magnitude and direction of such positional disagreement, a plurality of thermionic relays having plate circuits selectively controlling said control motor, one of said relays being responsive to voltage in one direction and the other relay being responsive to voltage in the opposite direction, means for impressing said signal voltage jointly on said relays for energizing the control motor to cause said power means to drive the controlled member into positional agreement with the controlling member, means responsive to a positional disagreement between said members in excess of the said predetermined positional disagreement for impressing additional voltage on said relays to energize said control motor to cause said power means to move the controlled member to said predetermined positional disagreement for assumption of control by said first responsive means, and means responsive to the speed of said control motor for varying said signal voltage to effect damping of the movement of the controlled member.

13. In a system for positioning a controlled member in accordance with a controlling member, the combination of driving power means for the controlled member, a control motor therefor, means responsive to a predetermined positional disagreement between said members for inducing a signal voltage corresponding in magnitude and direction to the magnitude and direction of such positional disagreement, a plurality of thermionic relays having plate circuits for controlling said control motor, one of said relays being responsive to voltage in one direction and the other relay being responsive to voltage in the opposite direction, means for impressing said signal voltage on said relays for energizing the control motor to cause said motive means to drive the controlled member into positional agreement with the controlling member, second means responsive to a positional disagreement between said members in excess of the said predetermined disagreement for selecting a source of additional voltage of a polarity depending on the direction of said excessive positional disagreement, and means for impressing the voltage of said second responsive means on said relays for energizing the control motor to cause said power means to drive the controlled member to said predetermined positional disagreement for assumption of control by said first responsive means.

14. In a system for positioning a controlled member in accordance with a controlling member, the combination of a driving power means for the controlled member, a control motor therefor, an electrical differential operatively connected to said members and responsive to a predetermined positional variation between them, a second electrical differential operatively connected to said members and responsive to a positional variation between them in excess of the said predetermined variation, an electrical controller energized by said first differential for energizing said control motor to cause said power means to position said controlled member in accordance with the movement of the controlling member, and switching means actuated by said second differential for impressing a selected voltage on said controller to additionally energize said control motor to cause said power means to drive said controlled member to said predetermined positional variation for assumption of control by said first electrical differential.

15. In a system for positioning a controlled member in accordance with a controlling mem-

ber, the combination of a driving power means for the controlled member, a control motor therefor, an electrical differential operatively connected to said members and responsive to a predetermined positional variation between them, a second electrical differential operatively connected to said members and responsive to a positional variation between them in excess of the said predetermined variation, a plurality of thermionic relays having plate circuits controlling said power motor, one of said relays being responsive to voltage in one direction and the other relay being responsive to voltage in the opposite direction, means for impressing the output of said first differential on said relays to drive the controlled member into positional agreement with the controlled member, and means actuated by said second differential for applying additional voltage to said relays of a polarity depending upon the direction of said excessive positional variation to drive the controlled member to said predetermined positional variation for assumption of control by said first differential.

16. In a system for positioning a controlled member in accordance with a controlling member, the combination of a variable speed power device for driving said controlled member, a reversible electric motor for positioning the variable element of said device, an electrical differential responsive to the degree and direction of a predetermined positional variation between said members for developing a signal voltage of proportional magnitude and direction, means for applying said signal voltage to said control motor for rotating it through an angle in a direction corresponding to the magnitude and direction of said second voltage to cause said power device to drive said controlled member in accordance with the movement of said controlling member, a source of direct current potential, a polarity selector switch interposed between said source and said voltage-applying means, a second electrical differential responsive to the direction of a positional variation between said members in excess of the said predetermined positional variation for actuating said switch to impress a voltage on said voltage-applying means of a polarity corresponding to the direction of said excessive positional variation for positioning the variable element of said device to drive the controlled member to said predetermined positional variation for assumption of control by said first responsive means.

17. In a system for positioning a controlled member in accordance with a controlling member, the combination of a variable speed power device for driving said controlled member, a reversible electric motor for positioning the variable element of said device, an electrical differential responsive to the degree and direction of a predetermined positional variation between said members for developing a signal voltage of proportional magnitude and direction, means for applying said signal voltage to said control motor for rotating it through an angle in a direction corresponding to the magnitude and direction of said second voltage to cause said power device to drive said controlled member in accordance with the movement of said controlling member, a second electrical differential responsive to the direction of a positional variation between said members in excess of the said predetermined positional variation, a commutator switch actuated by said second differential in a direction corresponding to the direction of said excessive posi-

tional variation, a normally-closed contact for said switch interposed between said first electrical differential and said voltage-applying means, and two normally open contacts for said switch, each interposed between an independent source of voltage and said voltage-applying means, whereby said first differential is disconnected from said voltage-applying means and one or the other of said independent voltage sources connected thereto by said second differential upon excessive positional variation and depending upon the direction of said excessive variation for causing said motor to control said variable speed power device to drive the controlled member to said predetermined positional variation for assumption of control by said first responsive means.

18. In a system for positioning a controlled member in accordance with a controlling member, the combination of a variable speed power device for driving said controlled member and having a movable control element, a reversible electric motor for positioning said element, an electrical differential responsive to the degree and direction of a predetermined positional variation between said members for developing a voltage of corresponding magnitude and direction, a pair of thermionic relays having independent plate circuits for controlling the direction of rotation of said motor, one of said relays being responsive to voltage in one direction and the other relay being responsive to voltage in the opposite direction, means for applying said signal voltage to said relays, for energizing said motor to position the control element of said gear to drive the controlled element the corresponding angle and direction into positional agreement with said controlling member, a second electrical differential responsive to the direction of a positional variation between said members in excess of said predetermined positional variation, a switch actuated by said second differential in a direction corresponding to the direction of said excessive positional variation, a normally closed contact for said switch interposed between said first electrical differential and said voltage-applying means, and two normally open contacts for said switch each interposed between one of said thermionic relays and a source of voltage of corresponding polarity, whereby said first differential is disconnected from said voltage-applying means and one of said voltage sources is connected thereto by operation of said switch by said second differential upon excessive positional variation between said members and depending upon the direction of said excessive variation for energizing said motor to rotate in the corresponding direction for positioning the control element to cause said power device to drive the controlled member to said predetermined positional variation for assumption of control by said first responsive means.

19. In a position control system, a controlling object, a controlled object and means for moving said controlled object substantially in positional agreement with said controlling object comprising means for driving said controlled object and means for controlling said driving means in accordance with the positional disagreement of said controlled and controlling objects and with the first and a higher time derivative of the motion of said controlling object.

20. In a position control system, a controlling object, a controlled object, electrical means for driving said controlled object, means for gen-

erating a signal E. M. F. having components proportional to the positional disagreement of said controlling and controlled objects and to the first and a higher time derivative of the motion of said controlling object, and means for controlling said driving means in accordance with said signal E. M. F.

21. In a position control system, a controlling object, a controlled object, means for driving said controlled object, means for generating a signal E. M. F. proportional to the positional disagreement of said controlling and controlled objects, means for generating signal E. M. F.'s proportional to a series of time derivatives of the motion of said controlling object, means for combining said signal E. M. F.'s, and means for controlling said driving means in accordance with said combined signal E. M. F.

22. In an electrical position control, a controlling object, a controlled object and means for moving said controlled object substantially in positional agreement with said controlling object, comprising means for driving said controlled object, means for generating a signal E. M. F. having components proportional to the positional disagreement of said controlled and controlling objects and to the first and second time derivatives of the motion of said controlling object and means for controlling said driving means in accordance with said combined signal E. M. F.

23. In a remote position control system for controlling the setting of one element to bear a predetermined relation to another element, a sending element, a responding element, means for driving said responding element and control means for controlling said driving means in accordance with the lag in the following, and in accordance with the velocity and acceleration of said sending element.

24. In a remote position control system for controlling the setting of one element to bear a predetermined relation to another element, a sending element, a responding element, means for driving said responding element and control means for controlling said driving means in accordance with the lag in the following, and in accordance with the acceleration of said sending element.

25. In a remote position control system for controlling the setting of one element to bear a predetermined relation to another element, a sending element, a responding element, means for driving said responding element and control means for controlling said driving means in accordance with the lag in the following, and in accordance with the velocity and a higher derivative of the velocity of said sending element.

GEORGE AGINS.
